UNITED STATES PATENT OFFICE.

GOMER W. PRICE AND CURT F. ZIMANSKY, OF SAN FRANCISCO, CALIFORNIA,
ASSIGNORS TO G. W. PRICE PUMP AND ENGINE COMPANY, OF SAN FRANCISCO, CALIFORNIA.

WELL-PUMP CONSTRUCTION.

Application filed May 21, 1921, Serial No. 471,457. Renewed March 17, 1923.

To all whom it may concern:

Be it known that we, GOMER W. PRICE and CURT F. ZIMANSKY, citizens of the United States, residing in the city and county of San Francisco and State of California, have invented a new and useful Improvement in a Well-Pump Construction, of which the following is a specification.

Our invention relates to improvements in well pump construction wherein a pump shaft casing operates in conjunction with a discharge casing to produce a rigid supporting structure for the pump shaft to prevent whipping or lateral movement of said shaft.

The primary object of the present invention is to provide a new and improved construction for well pumps adapted to provide a rigid support for a pump shaft extending therethrough.

A further object is to provide a new and improved device of the character described which may be easily and readily disassembled and reassembled without changing the relative positions of the several parts.

It is also an object to provide improved means embodied within a pump shaft casing and a discharge casing for providing a rigid supporting structure for a pump shaft to prevent lateral movement or "whipping" of said shaft.

A still further object of our invention is to provide a device of the character described having improved means for centering a discharge casing and a pump shaft and casing therefor in such a manner that the discharge casing may be placed under a tension and the shaft casing under compression whereby the reaction of both stresses will provide a rigid supporting structure and resist lateral movement of the several parts.

We accomplish these and other objects by means of the improved device disclosed in the drawings forming a part of the present specification wherein like characters of reference are used to designate similar parts throughout the said specification and drawings, and in which:

Figs. 1 and 1^a are broken vertical sectional views of a deep well pump disclosing our improved construction; and

Fig. 2 is an enlarged broken vertical sectional view of a portion of the well casing, discharge casing, shaft and shaft casing.

Referring to the drawings the numeral 1 is used to designate a well casing within 55 which is centered and suspended a discharge casing 2 having a suitable pump 3 attached to the lower end thereof, said discharge casing being in turn suspended from an outlet casting 4.

The discharge casing 2 is composed of sections connected by means of flanges 6 secured together by suitable bolts 7 and each set of flanges having an annular recess 8 therein within which is slidably mounted the 65 rim 9 of a spider 10 provided with a hub or bearing 11 having annular shoulders 12 arranged on each end of said hub 11 and concentric with the periphery of the rim 9, said flanges 6 holding adjacent ends of adjacent 70 sections of the discharge casing 2 in spaced relation to permit movement of the spiders 10, which are arranged or provided at regular intervals throughout the length of the structure, within the annular recesses 8, the 75 purpose of which will hereinafter be more fully set forth. The spider 10 and its mounting is fully described in a co-pending application, Serial Number 471,460, May 21st, 1921, patented Jan. 30, 1923, No. 1,443,516 80 reference to which is hereby made.

A sectional pump shaft 14 is connected at its lower end to the runners, not shown, of the pump 3 and the upper end of said shaft is provided with a suitable pulley 16 by 85 means of which said shaft 14 may be rotated.

To enclose the pump shaft 14 and bearings 11 from the water in the discharge casing 2 we have provided sectional pump shaft casings 17 of substantially the same length as 90 the lengths of the discharge casing 2, the adjacent ends of adjacent shaft casings engaging the shoulders 12 on opposite ends of the same bearing 11, whereby said shaft casings 17 may be centered relatively to the pump 25 shaft 14 and the discharge casing 2.

The lower end of the lowermost shaft section 17 is seated upon a similar annular shoulder 18 arranged on the upper end of the pump 3 while the upper end of the uppermost shaft casing section is similarly seated within a shoulder 19 arranged in the lower portion of a thrust bearing member 20 which is slidably mounted within a frame 21, resting upon the outlet casting 4, and 100 movable relatively to said frame 21 by means

of suitable screws 22 rotatably mounted within said frame 21 and screw threaded into the thrust bearing member 20, the purpose of which will hereinafter be more fully described.

After the several sections of the discharge casing 2, spiders 10, shaft 14 and shaft casing 17 are assembled and in position within the well, the screws 22 are operated to move the bearing member 20 downward, which action will place the shaft casing sections under compression and clamp said sections between their respective shoulders, to produce a tight fit between said shaft casing sections and shoulders, and simultaneously place the sections of the discharge casing 2 under tension, the spiders 10 moving within their respective annular channels 8 of the pipe flanges 6 to adjust the several parts relatively to each other.

It is the combination of the discharge casing 2 under tension and the shaft casing 17 under compression which produces a rigid structure to rigidly support the shaft 14, and thereby prevent lateral movement of said shaft 14 as well as of the discharge and shaft casings 2 and 17 respectively.

In other words, the shaft casing 17 is rigidly held in compression or trussed by the tension of the discharge casing 2.

The provision of the flanges 6 to connect the sections of the discharge casing 2 is an important feature of the invention as by means of this arrangement the lengths of the said sections, after initial assembling, is maintained so that the several parts of the structure may be readily and easily reassembled, when removed for repairs or other purposes, in the same or original relative positions, thereby eliminating the necessity for readjustment after such reassemblage.

As the spiders 10 are movably mounted within the discharge casing 2 it is evident that the compression of the shaft casing 17 may be adjusted relatively to said discharge casing 2 without disturbing the said discharge casing. It is obvious, then, that the joints between adjacent ends of the shaft casing sections 17 may be tightened without disturbing the discharge casing 2 or the shaft 14 for the reason that said shaft 14 is slidably as well as rotatably mounted within the bearings 11 of the spiders 10.

This novel arrangement also provides an inherent circulatory lubricating system for the shaft 12 and bearings 11, wherein a lubricant introduced by means of the pipe 23 to the upper section of the shaft casing 17 circulates through said shaft casing 17 and bearings 11, and spent lubricant is dispensed through a channel 24 into the well, the subject matter of which is covered in a copending application.

It is obvious from the foregoing that we have provided a new and improved structure

for well pumps wherein a rigid support is provided to center the shaft and shaft casing within a discharge casing and arranged to prevent lateral movement of said shaft.

It is also obvious that the several parts may be disassembled and easily and readily reassembled without requiring readjustment of the several parts.

Having thus described our invention what we claim as new and desire to secure by Letters Patent is:

1. A well pump construction comprising a discharge casing; a shaft rotatably mounted and centered within said casing; a shaft casing enclosing the shaft; and means for placing the shaft casing under a compression and the discharge casing under tension to truss said shaft casing whereby a rigid support may be provided for the shaft.

2. A well pump construction comprising a discharge casing; bearings slidably mounted at intervals within the discharge casing; a shaft rotatably and slidably mounted within the bearings; shaft casing sections enclosing said shaft and clamped between the bearings in the discharge casing; and means for retaining the shaft casing sections under compression to produce a tension in the discharge casing whereby said shaft casing sections may be trussed by said discharge casing to provide a rigid support for the bearings and shaft therein.

3. A well pump construction comprising a discharge casing arranged in sections; flanges connecting said sections with their ends in spaced relation and having annular channels in said flanges; bearings slidably mounted within said annular channels; a shaft rotatably and slidably mounted within said bearings; shaft casing sections enclosing said shaft and clamped between said bearings; and means for moving said shaft casing sections and bearings to place said sections under compression and the discharge casing sections under tension whereby said shaft casing sections may be trussed by said discharge casing sections to provide a rigid supporting structure for, and to prevent lateral movement of, said shaft and shaft casing.

4. The combination with a well pump of a discharge casing arranged in sections; flanges connecting said sections in spaced relation whereby said sections may be reassembled in the same relative position to other portions of said pump; a pump shaft slidably and rotatably mounted within said discharge casing; a shaft casing enclosing said shaft; and means for placing the shaft casing under compression to provide a tension in the discharge casing whereby said shaft casing may be trussed by said discharge casing to provide a rigid supporting structure for the shaft to prevent lateral movement of the same.

5. The combination with a well pump of a discharge casing; a shaft rotatably mounted within the discharge casing and connected to the pump; spiders mounted within the discharge casing and rotatably engaging the shaft; a shaft casing enclosing the shaft and connected to the spiders; and means for placing the discharge casing under tension whereby the same may operate in conjunction with the spiders to truss said shaft casing and thereby provide a rigid support to prevent lateral movement of the shaft and shaft casing within the discharge casing. 45
10. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 50
15. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 55
20. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 60
25. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 65
30. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 70
35. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 75
40. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 80
7. The combination with a well pump of a discharge casing connected to said pump; a shaft centered within said discharge casing and connected to the pump; an outlet casting mounted at the top of the discharge casing; a member slidably mounted on said casting; a shaft casing enclosing said shaft and connected to the slidable member and to the pump; means for moving the slidable member to clamp the shaft casing between the pump and slidable member whereby said shaft casing may be placed under compression and the discharge casing under tension to truss said shaft casing; and spiders slidably mounted at intervals within the discharge casing and rotatably and slidably engaging and centering the shaft to prevent lateral movement thereof relatively to the discharge casing. 85
45. The combination with a well pump of a sectional discharge casing; flanges connecting adjacent ends of adjacent sections in spaced relation; a pump shaft centered within the casing; spiders slidably engaging the casing and rotatably supporting the shaft; a sectional shaft casing mounted between the spiders to enclose the shaft from the discharge casing; and means for compressing the casing sections between the spiders. 90

In witness whereof we hereunto set our signatures.

GOMER W. PRICE.
